UNITED STATES PATENT OFFICE.

RICHARD VALENTINE, OF JANEVILLE, WISCONSIN.

FOUNTAIN-PEN.

SPECIFICATION forming part of Letters Patent No. 440,077, dated November 4, 1890.

Application filed May 5, 1890. Serial No. 350,593. (No model.)

To all whom it may concern:

Be it known that I, RICHARD VALENTINE, a citizen of Janesville, in the county of Rock and State of Wisconsin, have invented certain new and useful Improvements in Fountain-Pens; and I do hereby declare the following to be a full, clear, and exact description of the invention, such as will enable others skilled in the art to which it appertains to make and use the same.

My invention relates to an improvement in pens, and more particularly to that class known as "fountain-pens."

Many fountain-pens of which I am aware are defective in one or more of the following points, viz: The under-feeding pens are more or less complicated, will "skip," and are generally unreliable. The upper-feeding pens deprive the user of that fine elasticity and "gold-pen action" so much appreciated by lovers of gold pens, by reason of the rubber or metal top-feeding piece, which necessarily lags on the back or upper side of the nibs of the gold pen. Under-feeding pens are scanty and irregular, and top-feeding pens, if made to flow promptly when inverted for use, in a few weeks "drop" or "flood." The average fountain-pen is composed of a number of parts, and their profitable service is restricted.

The object of my invention is to obviate the objections of previous devices and produce a serviceable under-feeding fountain-pen.

A further object is to provide an improved under-feeding shaft adapted to feeding ink to the under side of the metal pen by the ink adhering to the feeding-shaft and under or concave face of the metal pen as it passes out of the barrel to feed to the under side of the nibs of the pen in writing.

A further object is to make a fountain-pen of few parts and practical utility, one by which to use a small gold pen, if desired, and preserve the appreciated gold-pen action by dispensing with all upper-feeding devices whatever.

With these objects in view the invention consists in certain novel features of construction and combinations and arrangement of parts, as hereinafter set forth and pointed out in the claims.

In the accompanying drawings, Figure 1 is

a longitudinal sectional view of the device. Fig. 2 is a cross-section through the head of the pen. Fig. 3 is a detached view of the feeding-shaft. Fig. 4 is a view of a modified form of shaft.

A represents the barrel of the pen, having an internally-screw-threaded portion at one end for the externally-screw-threaded shank 60 of the head B. The head B is provided internally, at a point in proximity to the free end thereof, with a flange a, having notches a' at points preferably below the center of the head. A pen C is inserted into the head 65 B, and is adapted to enter the notches a' of the flange a, and the pen wedged or secured in the head. Thus it will be seen that an open-air space b is formed over the pen, which space may be of larger size than the 70 opening a' beneath the pen, through which opening a' the forward end of a feeding-shaft D is made to project. The feeding-shaft is made in the form shown in Fig. 3, having a rear flat portion c adapted to receive ink 75 from the barrel, and at the forward end of the portion c the shaft is broadened to produce flanges c', whereby said shaft is permitted to fit closely within the head of the pen. From the flanges c' the shaft tapers gradually 80 and terminates in a point c'. The forward tapering end of the shaft D is passed through the opening a', terminating at a point in proximity to the ends of the nibs of the pen, said tapering portion being bent slightly to 85 cause it to lie in or nearly in contact with the pen. By thus arranging the feeding-shaft relatively to the pen the ink will be fed by capillary attraction of the ink to the shaft to the under face of the pen, the top 90 surface of the pen being kept dry, thereby producing a repellent surface, and in this manner preventing flooding of the pen, which is liable to occur where the ink is fed to both the upper and under faces of the pen.

Instead of making the feeding-shaft as above described, it may be made as shown in Fig. 4, having its upper or rear end bent back so as to secure it in the pen section or barrel.

By my construction the permanent air-opening above the metal pen permits a uniform atmospheric pressure, and the ink below this point is free to fall by gravitation, excepting as it is restrained by the law of adhesion of

liquids to solids, and is therefore as ready to flow as in the case when a metal pen is dipped, as was the custom more generally.

It will be noticed that the ink adheres to almost the entire surface of the feeding-shaft as it passes out of the barrel and is held underneath the pen for use.

Slight changes might be made in the details of construction of my invention without departing from the spirit thereof or limiting its scope. Hence I do not wish to restrict myself to the precise details herein described; but,

Having fully described my invention, what I claim as new and desire to secure by Letters Patent, is—

1. In a fountain-pen, the combination, with a barrel and a head, of a flange in the head, a pen fitted in the head and having bearing 20 in notches in the flange so as to leave an opening above the pen, and a feeding-shaft terminating on the under face of the pen, substantially as set forth.

2. In a fountain-pen, the combination, with 25 a head having an annular flange therein adapted to receive and hold a pen, of an ink-feeding shaft constructed to lie in one of the passages formed between the pen and flange

and adapted to conduct ink to the pen, substantially as set forth.

3. In a fountain-pen, the combination, with a barrel and head, the latter adapted to receive a pen which divides it into two air-passages of different sizes, of a feeding-shaft adapted for insertion into one of the passages, 35 one end of the shaft adapted to lie against the under surface of a pen and the other end projecting into the barrel, substantially as set forth.

4. In a fountain-pen, the combination, with 40 a barrel and a head, the latter having a flange therein, of a pen fitted in the head and having bearing in notches in the flange so as to leave an opening above and below the pen, and a feeding-shaft located below the pen and extending into the barrel, said shaft tapering at its outer end and having flanges between the ends, substantially as set forth.

In testimony whereof I have signed this specification in the presence of two subscribing witnesses.

RICHARD VALENTINE.
